UNITED STATES PATENT OFFICE.

FRANCIS NATHER, OF JOHNSTOWN, PENNSYLVANIA, ASSIGNOR TO THE LORAIN STEEL COMPANY, A CORPORATION OF PENNSYLVANIA.

SWITCH STRUCTURE.

No. 920,619.

Specification of Letters Patent.

Patented May 4, 1909.

Application filed May 12, 1908. Serial No. 432,546.

To all whom it may concern:

Be it known that I, FRANCIS NATHER, of Johnstown, in the county of Cambria and State of Pennsylvania, have invented a new and useful Improvement in Switch Structures, of which the following is a full, clear, and exact description, reference being had to the accompanying drawings, which form a part of this specification.

10 My invention relates to that type of switch structures known as tongue switches in which a tongue is pivotally mounted in the switch structure.

The object of my invention is to provide a 15 simple and efficient device whereby the heel or pivoted end of the tongue is held to its seat in the switch structure by means of an adjustable device whereby the wear of the heel of the tongue can be taken up.

20 With these objects in view, my invention consists in the novel construction, arrangement and combination of parts pointed out in the appended claims, and illustrated in the accompanying drawings, in which—

25 Figure 1, is a plan view of a portion of a switch structure embodying my invention; Fig. 2 is a section on the line II—II of Fig. 1; Fig. 3 is a similar view on the line III—III of Fig. 2.

30 A is a switch structure, and is provided with the usual tread and guard surfaces.

a is the tongue bed which is provided with an enlarged circular recess a'.

35 B, is the switch tongue having an enlarged circular heel b, and projecting therefrom, is a lug b' having portions cut away, as at b'', forming recesses for the purpose hereinafter described. This tongue B, is placed on the seat a of the switch structure A, and its circular heel b, is rotatably mounted in the circular recess a', with the projection b' extending through an orifice in the switch structure into a recess a'' below the tongue bed. Mounted within this recess a'', is the

40 lever C, which is fulcrumed on the projection a'', on the switch structure A. The one end of this lever C, is provided with a fork, and the opposite end C', is provided with a boss which is threaded to receive the screw D

45 50 having the jam nut D'. The forked end C' enters the cutaway portions b'' of the projection b' of the tongue B.

When the parts are completed and ready to be assembled, the tongue is dropped into

its position, and the lever C is inserted into 55 its position. The screw D is then put into the one end of the lever and screwed down to its proper place of adjustment after which the jam nut is run down to retain the screw in its position. As will readily be understood by reference to Fig. 2, the screw has a tendency to raise the one end of the lever, thereby depressing the forked end C, and with it the heel of the tongue. As the heel of the tongue becomes worn, the jam nut D' 60 is released, and the screw D is turned to elevate this end of the lever C, thereby taking up the wear at the heel of the tongue, after which the jam nut is again set to lock the screw D. To provide ready access to the 65 screw D, a removable cover is provided for the opening which is in communication with the recess a'', in the switch structure.

I do not wish to limit myself to the detail construction as shown and claimed, as various changes can be made, without departing from the spirit of my invention.

Having thus fully described my invention, what I claim as new, and desire to secure by Letters Patent, is:—

1. In a switch structure, a tongue having a projection with recesses, a lever, one end of which enters the recesses, and means to exert pressure on the other end.

2. In a switch structure, a tongue mounted therein, a fulcrumed lever, one end of which is in engagement with the tongue, and means to exert pressure on the other end to hold the heel of the tongue down.

3. In a switch structure, a tongue having a projection extending below the bottom of the tongue bed, a lever, one end of said lever engaging the projection, and a screw to raise the lever passing through the other end thereof.

4. In a switch structure, a movable tongue having a projection mounted thereon, said projection being provided with cutaway portions to receive the forked end of a lever, one end of said lever being provided with an adjusting screw.

In testimony whereof, I have affixed my signature in presence of two witnesses.

FRANCIS NATHER.
